MEDICINE DISPENSING TRAY
OR THE LIKE

Marilyn K. Costello, El Centro, Calif.
(413 Butler Ave., Chalfont, Pa. 18914)

Filed July 15, 1970, Ser. No. 23,964

Term of patent 14 years

Int. Cl. D24—02

U.S. Cl. D83—1

FIG. 1.

FIG. 2.

FIG. 1 is an upper left front perspective view of a medicine dispensing tray, showing my new design; and

FIG. 2 is a lower right front perspective view thereof.

The two cups and two cards shown in dotted outline are for illustrative purposes only.

I claim:

The ornamental design for a medicine dispensing tray or the like, substantially as shown and described.
